UNITED STATES PATENT OFFICE.

HENRY FLICK, JOHN P. VOELKER, AND HARRY DUNN, OF JACKSON, MICHIGAN.

FACING MACHINE FOR FACING THE CENTERS OF WOOD SPOKE WHEELS.

1,426,168.

Specification of Letters Patent. Patented Aug. 15, 1922.

Application filed October 14, 1921. Serial No. 507,761.

To all whom it may concern:

Be it known that we, HENRY FLICK, JOHN P. VOELKER, and HARRY DUNN, citizens of the United States, residing at Jackson, in the county of Jackson, State of Michigan, have invented certain new and useful Improvements in Facing Machines for Facing the Centers of Wood Spoke Wheels, of which the following is a specification.

10 This invention relates to improvements in facing machines for facing the centers of wood spoke wheels.

The objects of the invention are:

15 First, to provide an improved planer means for facing such wood wheel centers.

Second, to provide an improved feed means for advancing the wheel to the planer.

Further objects, and objects relating to details and economies of construction and 20 operation will definitely appear from the detailed description to follow.

The objects of the invention are accomplished by the devices and means described in the following specification. The invention is clearly defined and pointed out in 25 the claims.

A structure which is a preferred embodiment of the invention is fully illustrated in the accompanying drawing, forming a part 30 of this application, in which:

Fig. I is a perspective view of a wheel facing machine embodying the features of this invention.

Fig. II is a detail vertical sectional view 35 through the machine on a slightly offset plane corresponding to line 2—2 of Figs. III and IV.

Fig. III is a detail transverse sectional view on line 3—3 of Figs. II and IV, showing the clutch jaw actuating means.

Fig. IV is a detail side elevation view of the wheel clutch plate, the cutter head and the stop means and other parts being omitted for the sake of clearness.

45 In the drawing similar numerals of reference refer to similar parts throughout the several views and the sectional views are taken looking in the direction of the little arrows at the ends of the section lines.

50 Considering the numbered parts of the drawing by their numbers, 1 is the main

frame of the machine. 2 is the cutter head carried by shaft 3 in suitable bearings 4 driven by the belt and pulley 5 and 6 respectively.

Weighted press rolls 7 and 8 are provided for engagement with the revolving work to steady the same. 9 is a revolving circular disk work support provided with a central support 90 for the wheel center. A series 55 of radially adjustable clutch jaws 10 with depending shanks 11 center and clamp the wheels in place. Connecting links 12 from wrist pins 13 on segment gears 14 actuate the jaws. The segment gears 14 are actuated by segment gear 15, which is pivoted on journal 16 at the upper end of column 17 resting on flange 18. A lateral arm 19 on gear 15 is connected by piston rod 20 to the trunnioned air cylinder 21 whereby all 60 the jaws are actuated simultaneously for centering and clamping the metallic felly 65 wood wheel 22 when placed thereon.

The column 17 is a piston rod projecting 70 through the stuffing box 23 and is actuated by air cylinder 24. The column or piston rod is revolved by the gear 25, which is splined thereon at 26, being driven by the pinion 27 on shaft 28, the shaft being supported in the usual bearing 30—see Fig. I. 75 Tight and loose pulleys 29 are provided, the shifter 290 being controlled by small air cylinder 291 supplied from the throttle valve 35 hereafter to be described.

A vertical centering pin 32 with tapered point 33 is on the revoluble work table 9. A stop 34 corresponding to this pin 32 is carried by the overhanging framework above and serves to limit the upward movement of the work table with a wheel thereon, so that only the face of the hub portion of the wheel can be cut away by the revolving cutter head 2, which is disposed to one side of the center, the arrangement clearly appearing in Fig. IV.

80 A throttle valve 35 controlled by handle 36 is provided for the air supply through pipe 37 to the cylinder 24 and through pipe hose 38 to the cylinder 21, as clearly seen 85 in Fig. I.

90 Where one side of the wheel is true or has been dressed it is unnecessary to provide 95

the clutch for centering and holding the same, as the wheel can be pressed down upon the table and can be rotated by any suitable stop thereon. This is mentioned because in practice two machines are made use of in dressing and facing the centers of the wheels—one machine precisely as here illustrated with the clutch jaws for engaging the metallic felly, and the other with those parts omitted, it being unnecessary to clutch the wheel after one side has been faced.

It will thus be seen that the structure is capable of considerable variation without departing from my invention. It is desired to claim the structure specifically as well as broadly as pointed out in the appended claims.

Having thus described the invention, what is claimed as new and desired to secure by Letters Patent is:

1. The combination of a suitable framework, a revolving cutter head carried by an overhanging portion thereof, means for driving the same, a horizontal revolving work table disposed with a raised center to one side of the cutter head, a center stop pin therefor and a corresponding stop carried by the overhanging portion, clutch jaws radially disposed on the said plate with shanks projecting there-beneath, segment pinions with pitman connected to actuate said jaws simultaneously, a central segment gear meshing with the said pinions to actuate the same simultaneously, a trunnioned air cylinder carried on the under side of said plate connected to an arm on the central gear for operating the same, an upright air cylinder with a piston for carrying the said table to and from the said cutter head, a gear for revolving the plunger for rotating the said table, a tight and loose pulley with air actuated belt shifter, and air connections for simultaneously operating the said clutch and plunger cylinders, coacting as specified.

2. The combination of a suitable framework, a revolving cutter head carried by an overhanging portion thereof, means for driving the same, a horizontal revolving work table disposed with a raised center to one side of the cutter head, a center stop pin therefor and a corresponding stop carried by the overhanging portion, an upright air cylinder with a piston for carrying the said table to and from said cutter head, a gear for revolving the plunger for rotating said table, a tight and loose pulley with air actuated belt shifter, and air connections for operating the plunger cylinder, coacting as specified.

3. The combination of a suitable framework, a revolving cutter head carried by an overhanging portion thereof, means for driving the same, a horizontal revolving work table disposed with a raised center to one side of the cutter head, clutch jaws radially

disposed on the said plate with shanks projecting there-beneath, segment pinions with pitman connected to actuate said jaws simultaneously, a central segment gear meshing with the said pinions to actuate the same simultaneously, a trunnioned air cylinder carried on the under side of said plate connected to an arm on the central gear for operating the same, an upright air cylinder with a piston for carrying the said table to and from the said cutter head, a gear for revolving the plunger for rotating the said table, a tight and loose pulley with air actuated belt shifter, and air connections for simultaneously operating the said clutch and plunger cylinders, coacting as specified.

4. The combination of a suitable framework, a revolving cutter head carried by an overhanging portion thereof, means for driving the same, a horizontal revolving work table disposed with a raised center to one side of the cutter head, an upright air cylinder with a piston for carrying the said table to and from said cutter head, a gear for revolving the plunger for rotating the said table, a tight and loose pulley with air actuated belt shifter, and air connections for operating the plunger cylinder, coacting as specified.

5. The combination of a suitable framework, a revolving cutter head carried by an overhanging portion thereof, means for driving the same, a horizontal revolving work table disposed with a raised center to one side of the cutter head, a center stop pin therefor and a corresponding stop carried by the overhanging portion, clutch jaws radially disposed on the said plate with shanks projecting there-beneath, segment pinions with pitman connected to actuate said jaws simultaneously, a central segment gear meshing with the said pinions to actuate the same simultaneously, a trunnioned air cylinder carried on the under side of said plate connected to an arm on the central gear for operating the same, and means for raising said revolving work table to and from the cutter head, coacting as specified.

6. The combination of a suitable framework, a revolving cutter head carried by an overhanging portion thereof, means for driving the same, a horizontal revolving work table disposed with its center to one side of the said cutter head, clutch jaws radially disposed on the said plate with shanks projecting there-beneath, segment pinions with pitman connected to actuate said jaws simultaneously, a central segment gear meshing with the said pinions to actuate the same simultaneously, a trunnioned air cylinder carried on the under side of said plate connected to an arm on the central gear for operating the same, and means for raising said revolving work table to and from the cutter head, coacting as specified.

7. In a machine of the class described, the combination of a revolving cutter head, a revoluble work table with its center to one side of said cutter head, an air cylinder to raise said table to the cutter head, tight and loose pulleys with air actuated belt shifter to drive the table, a throttle valve to

actuate both said air cylinder and shifter, as specified.

In witness whereof, we have hereunto set 10 our hands and seals.

HENRY FLICK. [L.S.]
JOHN P. VOELKER. [L.S.]
HARRY DUNN.
